UNITED STATES PATENT OFFICE.

BENJAMIN EDWARD MEACHAM, OF LORAIN, OHIO, ASSIGNOR TO AMERICAN STOVE COMPANY, OF ST. LOUIS, MISSOURI, A CORPORATION OF NEW JERSEY.

BURNER FOR WATER-HEATERS.

1,143,057.

Specification of Letters Patent. Patented June 15, 1915.

Application filed January 21, 1915. Serial No. 3,553.

To all whom it may concern:

Be it known that I, BENJAMIN E. MEACHAM, a citizen of the United States, residing at Lorain, in the county of Lorain and State of Ohio, have invented certain new and useful Improvements in Burners for Water-Heaters, of which the following is a specification, reference being had thereto to the accompanying drawing.

10 My invention relates to improvements in burners for water heaters.

The object of my invention is to provide an improved burner in which the mixing cone is well protected from condensation and overheating, and at the same time provide a burner in which there will be no back fire.

Another object of my invention is to provide a burner of this character which is 20 easy to assemble and repair and which has no packed or cemented joints, and at the same time produce a cheap and effective burner which will properly distribute the heat and cause perfect combustion.

25 A still further object of my invention is to provide a simple, cheap and effective burner of this character having certain details of structure and combination of parts hereinafter more fully set forth.

30 Referring now to the accompanying drawings; Figure 1 is a perspective view of my improved burner. Fig. 2 is a transverse vertical sectional view taken on the line 2-2, Fig. 1. Fig. 3 is a longitudinal vertical sectional view taken at right angles to Fig. 2, taken on the line 3-3, Fig. 2. Fig. 4 is an enlarged perspective view of a gas supply tube and the burner supporting base. Fig. 5 is a perspective view of a shutter for 40 regulating the air to the gas supply tube.

Referring now to the drawings, 1 represents the gas and air supply tube of my improved burner which is of an elongated form and has at its lower end the enlarged outwardly flared air-bell 2, all of which is of the usual construction of burners of this character. The lower end of the air-bell is provided with a beading 3, and opposite said beading the air-bell has an end closure 4, which is provided with the downwardly extending cylindrical neck 5. This cylindrical neck 5 forms an opening 6 through which the gas passes to the tube 1 and thence to the burner, as will be hereinafter more fully described.

The closure 4 is provided with two oppo-

sitely arranged air-inlet openings 7 by means of which air is supplied to the tube.

Surrounding the cylindrical neck 5 is a cylindrical collar 8, which is provided at its upper end with an outwardly extending annular shutter 9, provided with openings 10 adapted to register with the openings 7. This shutter 9 rests flat against the closure 4 of the air-bell and is rotatably mounted on 65 the neck.

The lower side of the shutter 9 is provided with a rib 11, provided at its outer end with the upwardly extending lug 12, which extends upwardly beyond the beading 3, and has passing therethrough a set screw 13, which is adapted to engage the outer face of the flared air-bell 2, beyond the beading 3, and thus the shutter is free to revolve upon the neck 5, but locked 75 against downward movement thereon. By this construction it will be seen that the shutter may be rotated or oscillated so as to bring the openings 10 to register with the openings 7 so that the amount of air passing 80 to the tube 1 is readily regulated. The set screw 13 is tightened when the shutter has been adjusted to its proper position and thus the proper amount of air is supplied to the tube.

85 The upper end of the tube 1 is provided with a circular base 14, having on opposite sides the outwardly extending ears 15 and 16 having slots 17 and 18.

The upper face of the base is provided 90 with a central depressed portion 19 having the flange 20 formed therearound and which fits a perforated copper cone 21, which forms a mixing chamber for breaking up the particles of gas and causing them to 95 thoroughly mix with the air whereby the burner at the point of combustion is supplied with a properly mixed gas.

The burner head consists of a rectangular body portion 22, which has at its lower end 100 on opposite sides the outwardly flared walls 23 and 24, which form a central dome adapted to correspond with the base 14, and is adapted to rest upon the base on the outside of the flange 20 and form a tight joint 105 therewith. The walls 23 and 24 form a domed chamber and at its upper end is a support 25, which is adapted to engage the upper end of the cone and hold it in the depressed portion 19 of the base. Communicating with the domed chamber on opposite sides are openings 26 and 27 which commu-

nicate with the rectangular burner head 22, and whereby the gas after it has become thoroughly mixed with the air after passing through the cone 21, passes to the rectangular burner 22. The dome-shaped chamber formed by the walls 23 and 24 is provided with outwardly extending ears 28 and 29 which are arranged directly above the ears 15 and 16 and are provided with openings 10 30 and 31 through which the bolts 32 and 33 pass.

By this structure it will be seen that the mixing chamber is clamped tightly down upon the circular base 14 and the support 25 engaging the cone 21 holds the cone in the depressed portion 19 against displacement. The upper end of the rectangular burner head 22 is open as indicated at 34 and in which closely fits the distributor head 35. 20 This head is held in the open top of the burner head 22 by means of a pin 36. The distributor is preferably formed with a V-shaped groove at the top and has on opposite sides the obliquely arranged curved 25 grooves 37 and 38 arranged on opposite sides which form passages to allow the escape of gas from the burner head. The gas is burned at the outlets of the grooves 37 and 38.

30 By this construction and arrangement of parts as herein shown, it will be seen that applicant has produced a burner in which the parts are readily assembled or disassembled, and in which a tight joint is made 35 to prevent the leakage of gas therefrom, and by the arrangement of the copper cone-shaped mixing chamber 21, it will be seen that the air and gas is thoroughly broken up and mixed as it passes therefrom and 40 enters the rectangular burner head 22 in a combustible gas. It thence passes from the rectangular burner head 22 out through the grooves or passages 37 and 38 and is burned.

Having thus described my invention what 45 I claim and desire to secure by Letters Patent is:

1. A burner of the character described, comprising a burner head having an open upper end, a distributor head removably secured in the open upper end of the burner head, the lower end of the burner head having a dome-shaped portion, a base having a circular portion closing the lower end of the dome-shaped portion of the burner head and having a combined air and gas supply tube, a perforated cone carried by the circular base portion and extending within the dome-shaped portion of the burner head, and means for fastening the 50 base and burner head together.

2. A burner comprising a burner head having an open upper end, a distributor head removably secured in the open end of the burner head, the lower end of the burner head having a dome-shaped portion in com-

munication therewith, a base having a circular portion closing the dome-shaped portion of the burner head, a perforated cone carried by the base and extending into the dome-shaped portion of the burner head, 70 oppositely arranged ears carried by the burner head and the base, bolts securing the ears together, and a combined air and gas supply tube carried by the base and adapted to supply the open lower end of the perforated cone with air and gas, substantially as shown and described.

3. A burner comprising a rectangular burner head, having an open upper end, a distributor head within the open upper end 80 of the burner head, the lower end of the burner head having a dome-shaped portion in communication therewith, a base having a circular portion closing the lower end of the dome-shaped portion of the burner head 85 and having a central depressed portion, a perforated cone carried by the depressed portion of the base and extending within the dome-shaped portion of the burner head and spaced therefrom, means for securing the base and the burner head together, and a combined air and gas supply for the base adapted to supply the lower end of the perforated cone with gas and air.

4. A burner comprising a rectangular burner head, having an open upper end and from which the gas is adapted to burn, a dome-shaped portion formed integral with the lower end of the burner head and in communication therewith, a base having a 100 circular portion closing the lower end of the dome-shaped portion and having a central depressed portion, a perforated cone within the depressed portion and extending upwardly within the dome-shaped portion of the burner head and engaging the upper end thereof, means for securing the burner head and the base together, and a combined air and gas supply tube carried by the base and communicating with the open lower end 105 of the perforated cone.

5. A burner comprising a rectangular burner head having an open upper end from which the gas is adapted to burn, said burner head having a dome-shaped central portion in communication therewith and having an open lower end, a base comprising a circular portion and adapted to close the lower end of the dome-shaped portion of the burner head and having a central depressed portion, a perforated cone carried by the depressed portion of the base and having its apex engaging the upper end of the dome-shaped portion of the burner head and spaced from the walls thereof, outwardly 115 extending ears carried by the base and the burner head, bolts passing through the said ears for clamping the base to the burner head and holding the perforated cone in its proper position therein, and a combined air 120 supply tube carried by the base and adapted to supply the open lower end of the perforated cone with air and gas.

and gas supply for the base for supplying air and gas to the lower open end of the perforated cone.

6. A burner of the character described, comprising a rectangular burner head having an open upper end, a distributor head removably secured in the open upper end, said burner head having a dome-shaped lower end in communication therewith, ears carried by the burner head, a base having a circular portion closing the lower end of the dome-shaped portion of the burner head and having a central depressed portion, a cone within said depressed portion and extending upwardly within the dome-shaped portion of the burner head and spaced therefrom and having its apex engaging the apex of

the dome-shaped portion of the burner head, outwardly extending ears carried by the base opposite the ears carried by the burner head and having slots therein, bolts passing through the slots in the ears of the base and through the openings in the ears carried by the burner head, and a combined air and gas supply for the base at a point opposite the center of the open end of the perforated cone, substantially as shown and described. 20 25

In testimony whereof I hereunto affix my signature in the presence of two witnesses.

BENJAMIN EDWARD MEACHAM.
